US0D1055695S

(12) United States Design Patent (10) Patent No.: US D1,055,695 S
(45) Date of Patent: * Dec. 31, 2024

(54) BOTTLE

- (71) Applicant: PepsiCo, Inc., Purchase, NY (US)
(72) Inventors: Michael Andrew Lohmeier, Chicago, IL (US); Ivan Pierre, Octeville sur Mer (FR)
(73) Assignee: PepsiCo, Inc., Purchase, NY (US)
() Term: 15 Years
(21) Appl. No.: 29/904,416
(22) Filed: Oct. 6, 2023

Related U.S. Application Data

- (63) Continuation of application No. 29/795,579, filed on Jun. 18, 2021, now Pat. No. Des. 1,002,384.

(57) CLAIM

The ornamental design for a bottle as shown and described.

DESCRIPTION

FIG. 1 is a top perspective view of a first embodiment of a bottle showing the claimed design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of a second embodiment of a bottle showing the claimed design;

FIG. 10 is a bottom perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The dashed broken lines in the figures show portions of the bottle that form no part of the claimed design.

The dot-dash broken lines in the figures show boundaries that form no part of the claimed design.

1 Claim, 14 Drawing Sheets
